UNITED STATES PATENT OFFICE.

JOSEPH JAMES BUTLER, OF NEAR SELECT, KENTUCKY.

COMBINED PITCHFORK AND RAKE.

SPECIFICATION forming part of Letters Patent No. 337,740, dated March 9, 1886.

Application filed August 6, 1885. Serial No. 173,748. (No model.)

To all whom it may concern:

Be it known that I, JOSEPH JAMES BUTLER, a citizen of the United States, residing near Select, in the county of Ohio and State of Kentucky, have invented certain new and useful Improvements in a Combined Pitchfork and Rake; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of this improvement is a pitchfork that may be conveniently adjusted to and securely held at a suitable angle to its handle and back, for the purpose of adapting it for use either as a fork or rake. These results are attained by the mechanism illustrated in the drawings herewith filed as part hereof, in which the same letters of reference denote the same parts in the different views.

Figure 1 is a perspective view of a pitchfork and handle embodying the features of my improvement. Fig. 2 is a similar view with part broken away, and showing the fork adjusted at an angle to the handle. Fig. 3 is a perspective representation, with parts broken away, more fully illustrating the construction of the fork's shank.

A is the handle, provided at the fork end with a slotted head, B, made of metal, secured to the handle A by the ordinary means of shank or socket, as may be deemed best.

C is the fork, having a shank, D, corresponding in size to the slot in the metal head B, to which it is pivotally connected, as shown at d.

D' is an integral extension of the shank D, arranged to engage with and bear against the inner end of the slot in the metal head B, as shown in Fig. 2, when the fork is adjusted for use as a rake.

A' is a spring, secured to the handle of the rake by flanged end a and staple a', or other suitable means, and provided at its forward end, a², with an inward flange, which extends through a perforation in the side of the metal head B, and by entering a perforation in the shank D, provided for the purpose, locks the fork in the position shown in Fig. 1. The shank D is provided with a similar perforation in a position to correspond with and receive the inward extension, a², of the spring A', and be locked in position thereby when the fork is in the position shown in Fig. 2, in which case its position will be braced and additionally secured by the extension D' of the shank D, engaging with the body of the metal head B at the inner end of the slot, as shown.

By disengaging the flange a² of the spring A' from the perforations mentioned in the shank D the fork may be readily adjusted to either of the positions shown, and the mechanism thus adapted for use either as a fork or rake.

Having explained the features of my improvement, what I claim as new, and desire to secure by Letters Patent, is—

The combination of the handle A, provided with the slotted head B and spring-latch A', and the fork C, pivoted to and within the slotted head B, and having a rectangular extension, D', perforated, as shown, and adapted to engage with and bear against the inner end of the slot in the head B, and brace the fork at an angle when adjusted for use as a rake, as specified.

In testimony whereof I affix my signature in presence of two witnesses.

JOSEPH JAMES BUTLER.
